GRATE FOR KITCHEN RANGES

Edward H. Williams, Bayside, and Paul F. Tunke,
Ridgewood, N. Y., assignors to The Welbilt
Stove Company, Incorporated, Maspeth, N. Y.,
a corporation of New York

Application July 31, 1945, Serial No. 607,970

3 Claims. (Cl. 126—214)

1

The present invention relates primarily to grates of the type that are usually employed on a kitchen range wherein the heat is supplied from an open flame, such as from a gas flame. Grates of this type, normally located on the top cooking surface of the stove or range, are employed to support the cooking utensils over the flame.

Heretofore grates of this type have usually been made by casting them from some suitable material such as cast iron. Cast iron grates, however, have the disadvantage of requiring considerable mass and weight of material in order to give sufficient strength, and also, such grates are easily broken.

One of the primary objects of the present invention is to provide a grate made of sheet metal that may be used in conjunction with an open flame kitchen range.

Another object of the invention is to provide such a sheet metal grate which may be made by a stamping operation.

Still another object of the invention is to provide a sheet metal grate which will not warp or become distorted when subjected to heat. To this end the sheet metal grate is so constructed that the stresses set up therein when in use, as when a utensil is placed thereon, are not such as to cause bending of the grate. In other words, the component parts of the grate of the present invention are so arranged that they tend to reinforce one another to prevent undue bending or flexing of the grate while at the same time being so arranged that the grate can be produced by a simple stamping operation.

A more comprehensive understanding of the objects and advantages of the present invention will be apparent from the following description thereof wherein reference is made to the accompanying drawings in which:

Fig. 1 is a plan view of a grate constructed in accordance with the present invention;

Fig. 2 is a sectional view taken substantially on line 2—2 of Fig. 1 through the center of the grate;

Fig. 3 is a sectional view taken on line 3—3 of Fig. 1 through one of the radial arms of the grate;

Fig. 4 is a sectional view taken on line 4—4 of Fig. 1; and

Fig. 5 is a sectional view taken on line 5—5 of Fig. 1.

Referring first to Fig. 1, which shows in elevation the preferred form of a grate constructed in accordance with the present invention, it will

2

be noted that the grate comprises a circular center section, referred to generally hereinafter by reference numeral 11, and a plurality of radially extending arms indicated generally by reference numeral 12. The arms 12 extend outwardly from the center section 11. In the embodiment of the invention shown there are six arms 12 and it will be obvious that a grate could be constructed in accordance with the present invention employing fewer or more arms 12.

The center section 11, which is substantially circular, has an inner flange 13 which, as shown in Fig. 2, extends downwardly or toward the heating flame when the grate is employed in the

ordinary type of open flame kitchen range. The flange 13 increases the rigidity of the grate and in co-operation with other parts thereof hereinafter pointed out, assists in imparting to the grate the desired rigidity and prevents undue flexing or bending thereof when a weight, such as a heavy cooking utensil, is placed thereon. As will be apparent, the rigidity of the grate is maintained even though the parts thereof are heated to a high degree when the grate is in use.

15 The arms 12, as shown most clearly in the sectional view, Fig. 3, are throughout the greater part of their length in the form of an inverted U-shaped channel with the open side thereof presented to the flame over which the grate may

20 be placed. The side sections, such as 14, of the arms 12, as they approach the center section 11, bend outwardly therefrom as at 16, Figs. 1, 2 and 5, and merge into an outer flange 17 of the center section 11. The outer flange 17 extends downwardly in the same direction as the inner flange 13 of the center section 11. The sections of the outer flange 17 between adjacent arms 12 are substantially concentric with the inner flange 13.

25 The top surfaces of the inner ends of the arms 12 are raised above the flat disc surface of the circular center section 11, as shown more clearly in Figs. 2 and 4, and the top inner surfaces of the arms 12 are formed and bent so as to merge with the inner flange 13.

30 The feature of having the inner top surfaces of the arms 12 extend through the center section 11 and raised slightly thereabove enables this section of the arms and the center section to mutually reinforce one another and thereby impart rigidity to the structure in the center section thereof. Similarly, the two depending flanges 13 and 17 of the toroidally shaped center section co-operate with the flat disc-like section thereof to reinforce the same. Thus, no appre-

3

ciable bending of the grate through the center section 11 between the extending arms 12 will occur in the normal usage of the grate.

As shown more clearly in Fig. 2, the sides 14 of the arms 12 gradually increase in depth to a point near the outer extremities thereof, at which point the depth thereof is reduced. This shaping of the sides 14 of the arms 12 forms downwardly projecting lugs, such as 18, which assist in locating or positioning the grate in the opening in the top of the stove where the same is employed.

The sides 14 of the arms 12 at the extremities thereof are bent toward each other so as to form a rounded closed end on the part of the arms which will be located above the opening in the range where the grate is employed.

As will be noted in Fig. 2, the arms 12 slope slightly toward the center section so that a cooking utensil placed thereon will be supported, provided the bottom thereof is flat, at points adjacent the outer edge thereof.

From the above it will be evident that the invention provides a grate which is very light in comparison with grates for similar purposes made from castings, and which is extremely rigid and reinforced throughout by mutually co-operative parts to withstand all bending stresses that it might be subjected to in the normal use of such a grate. Furthermore, the above described grate is formed from a single blank of sheet metal, requiring no assembly of component parts thereof, as by riveting or welding, and in accordance with the teachings of the present invention, the strong and rigid but light grate may be easily and cheaply produced.

While the invention has been described herein with reference to but a single modification thereof, it will be apparent to those skilled in the art that various modifications thereof may be made without departing from the spirit or essential attributes thereof, and it is desired, therefore, that only such limitations be placed thereon as are specifically set forth in the appended claims.

What is claimed is:

1. A grate of the type described formed from a single blank of sheet metal, said grate comprising a substantially toroidally shaped center section having substantially flat web portions and a downwardly projecting inner flange and a plurality of arms extending substantially radially outwardly therefrom, said arms being substantially U-shaped in cross section and extending above said web portions to the inner flange of

said center section with said web in between the successive arms and said center section having an outer downwardly extending flange merging with the sides of said extending arms.

- 5 2. A grate of the type described formed from a single blank of sheet metal, said grate comprising a substantially toroidally shaped center section having substantially flat web portions and a downwardly projecting circular inner flange and

10 10 a plurality of arms extending substantially radially outwardly therefrom, said arms being substantially U-shaped in cross section with the inner ends thereof extending above said web portions and merging with the inner flange of said

15 15 center section with said web in between the successive arms, said center section also having an outer downwardly extending flange between said arms and merging with the sides thereof extending outwardly therefrom.

20 20 3. A grate of the type described formed from a single blank of sheet metal, said grate comprising a substantially toroidally shaped center section and a plurality of arms extending substantially radially outwardly therefrom, said center

25 25 section including inner and outer downwardly extending flanges and a web portion therebetween, said arms being substantially U-shaped in cross section and extending to the inner flange of said center section with the top surfaces of said

30 30 arms above the said web portion with said web portion in between the successive arms, said outer downwardly extending flange on said center section between said arms merging with the sides thereof extending outwardly therefrom, and said

35 35 arms having downwardly projecting positioning lugs adjacent the free ends thereof.

EDWARD H. WILLIAMS.
PAUL F. TUNKE.
